UNITED STATES PATENT OFFICE.

GEORGE C. BLICKENSDERFER, OF STAMFORD, CONNECTICUT; WILLIAM J. BLICKENSDERFER AND STEPHEN S. MAPES EXECUTORS OF THE WILL OF SAID GEORGE C. BLICKENSDERFER, DECEASED.

MACHINE FOR FILLING CARTRIDGE-BELTS.

1,358,699.

Specification of Letters Patent. Patented Nov. 16, 1920.

Application filed October 7, 1916. Serial No. 124,287.

To all whom it may concern:

Be it known that I, GEORGE C. BLICKENSDERFER, a citizen of the United States, residing at Stamford, county of Fairfield, 5 and State of Connecticut, have invented certain new and useful Improvements in Machines for Filling Cartridge-Belts, fully described and represented in the following specification and the accompanying drawings, forming a part of the same.

This invention relates to improvements in machines for filling cartridge belts.

The belts involved are ordinarily two long strips of canvas or the like, transversely 15 knit together at regular intervals to form loops, each loop being designed to receive and hold a cartridge.

In devices as heretofore known, a belt loop separator is provided which comprises 20 two pivoted members, each carrying a needle pointing in the direction of the line of the belt's travel and belt and needles are relatively moved in such manner that the needles penetrate the sides of each loop. 25 The cartridge being forced between the needle-carrying members, separates them slightly, and the needles thus being pulled apart, normally open the loop, so that the cartridge may be pushed into place by the 30 filling plunger. It has been found, however, that, due to hard spots in the belt and other causes, these needles will oftentimes fail to function, so that a loop, not being properly opened, fails to take the cartridge presented. 35 Such a break in the feed requires opening up the machine and setting the belt back, all of which involves delay and inconvenience. Furthermore, it often happens that the strain on the needles is so great that 0 they break and again the machine must be opened up and partially disassembled for substitution of new needles. In an endeavor to secure proper opening of each 5 loop in the case of new belts, many users take these belts that have not been used previously, and open each loop by means of some sharp instrument before attempting to run the belt through the filling machine. Such an operation obviously involves great 10 delay or the necessity of additional labor. It is the object of the present invention to obviate the above mentioned and similar objections and difficulties and to provide a belt filling machine having means for opening

the loops of the belt such that the operation 55 is at all times effective regardless of the character of the belt and such that the danger of needle breakage is avoided.

The following specification describes, and the accompanying drawing illustrates, a belt 60 filling machine constructed in accordance with this invention, it being understood that changes may be made in the form, construction and arrangement of the parts without departing from the invention, the form 65 herein shown being a preferred embodiment thereof.

In the drawing—

Figure 1 is a plan view of the belt filling device with parts in longitudinal section; 70

Fig. 2 is a cross-sectional view taken on the line 2—2 of Fig. 1 with parts broken away;

Fig. 3 is a cross-sectional view taken on the line 3—3 of Fig. 1;

Fig. 4 is an enlarged transverse sectional view showing the needle-carrying members;

Fig. 5 is a view in end elevation of the parts shown in Fig. 4; and

Fig. 6 is a view similar to that of Fig. 4 80 showing the parts in loop opening position.

Referring to the drawing, the machine has a base 7 which may be secured to a suitable table 8 or the like by screws 9. At one end of the base 7 is a belt guide 10 in the 85 form of a trough through which the belt feeds in a flat position. Associated with this trough is a pivoted clip 11 which is moved over to cover the belt and hold it in place. Just beyond the belt guide is a ratchet feed 90 wheel 12 having its periphery scalloped as at 13 to conform to the shape of the cartridges. This wheel is rotated step by step by a ratchet lever 14 which is pivoted to the base at 15, so that one end engages the edges 95 of the scalloped ratchet wheel. The other end is forked to embrace an eccentric cam 16 mounted on an operating shaft 17 which is rotated by a suitable handle 18 and crank 19. As this cam rotates, it acts first against 100 one branch and then the other, of the forked end of the ratchet lever to reciprocate the same. The downward stroke of the ratchet lever rotates the ratchet wheel one step, that is to say, the distance of one scallop, while 105 on its upward stroke, the lateral play of the lever is such as to allow it to move outwardly in sliding over the next scalloped

edge into a position for the next down stroke.

Located just above the ratchet wheel 12 is a similar scalloped wheel 20 rotating freely on a stud 21 carried by a hinged arm 22. In order to hold the wheel 20 yieldably in proximity to the wheel 12, the arm 22 carries a flat spring 23 which is held down, when the belt is in place by a latch member 24 pivoted to the base. When the loops containing cartridges, as shown in Fig. 3, are passed between the two wheels, due to the construction described, each advance step of the ratchet wheels feeds the belt forward the distance of one loop.

The invention includes means for seizing each side of the belt loop in a plurality of points in order to separate each loop, and in structures embodying the invention to the best advantage, these points are not all in alinement with the path of the belt's travel. Although capable of various constructions, in the form shown, pivoted to a plate 25 are two needle bars 26 which are normally pressed together by the forked end of a flat bar spring 27 which engages the slanting ends of these members. The front of the plate 25 is grooved centrally, as at 28, to receive the upturned edge of the belt guide 10 on which the plate slides. These needle bars 26 extend out beyond the plate 25, the outer ends being thickened and overlapping the end of the plate with a sliding tongue and groove connection. As appears in Fig. 4, these outer ends almost meet and the opposing edges are rabbeted as at 29 to provide space for passage of the belt. Extending into this space, to seize the belt, as hereinafter described, are a plurality of needles, two pair being shown in the present embodiment. The first pair of needles 30, as appears in Figs. 4 and 5, is held in grooves formed in the needle bars 26, by set screws 31 in such manner that they make a comparatively sharp angle with the plane of the belt and so that their points nearly meet. The needles 32 of the second pair are held in grooves just beyond the first pair by set screws 33, but these grooves are deeper and formed so that these needles are at a somewhat less sharp angle to the plane of the belt. It will be seen from Fig. 5 that the points of this second pair of needles, which also nearly meet, are offset from the points of the first pair as well as being in advance thereof.

Due to this construction, the belt loops will be seized on each side by two needles, the points of which are not in alinement with the path of the belt's travel, and, further, by needles having different angles with respect to the belt. As a result, the belt loops are always firmly seized and effectively opened both in the case of new

and used belts, and the tension is so distributed that there is no danger of needle breakage. To drive the needles into the belt, and to place the needle bars in a position to receive a cartridge, the plate 25 is advanced relatively to the belt for each loop presented. To this end, the plate 25 has in its back face a vertical groove 34 for receiving the end of one arm of a bell-crank lever 35, pivoted to the base at 36, the other arm of which contacts with a cam 37 mounted on the shaft 17. For each revolution of this shaft, the cam 37 displaces the bell-crank lever to advance the plate 25, far enough to drive the needles 30 and 32 into the sides of a loop of the belt. To open the loop thus seized by the needles, the needle-carrying members are forced apart by the advance of a cartridge 38. Secured above the base is a feed chute 39 (not shown) down which the cartridges are fed to a position on the base, as exemplified by the cartridge shown in Fig. 1. In this position the cartridge lies alongside of a pivoted carrier 39 which is moved to swing the cartridge over to a position in alinement with the belt loops. This movement of the carrier is caused by the stroke of a filling plunger 40 which has two shoulders 41 and 42 designed to engage a heel 43 on the carrier. This plunger 40 slides in a suitable groove 44 in the base and is driven by a crank 45 pinned to the cam 37 which, as before described, is rotated by the operating handle. As the plunger 40 makes its back stroke, the shoulder 41 strikes the heel 43 and swings the carrier to push the cartridge over to the position shown in dotted lines in Fig. 1, the cartridge pivoting against a pin 46. The plunger 40 has also a shoulder 47 and its back stroke brings this shoulder in a position to engage the rim of the cartridge. The forward stroke of the plunger, therefore, carries forward the cartridge toward the needle bars which have meanwhile been brought into proper alinement as before described. To receive the point of the cartridge, the rear faces of the ends of the needle bars 26 have complementary lips 48, as shown in dotted lines in Fig. 4. The point of the cartridge being advanced as just described, enters these lips and forces apart the members 26. This action, as will be clear, separates the points of the needles which penetrate the belt, as above described, and so open the loop, and upon the further advance of the cartridge, it is partially inserted in this opened loop, as shown in Fig. 6. Just after the loop has thus been opened, the cam 37 releases the bell-crank lever 35 and it is free to move back to its former position under the force of a double bar spring 49 which bears against it, as shown in Fig. 1. This same forward stroke of the

plunger 40 returns the carrier 39 to its former position by bringing the shoulder 42 in contact with the head 43. The carrier is held at the proper limits of its stroke either way by a V-shaped portion of spring 49 which bears against one side or the other of a pointed shoulder 50 on the carrier.

At this point, the cartridge being partially inserted in its loop, the belt is advanced one step, thus bringing the loop in question between the wheels 12 and 20, and the cartridge in alignment with the end of the plunger 40. On the next forward stroke of this plunger, it abuts against the rear end of the cartridge and drives it fully into place in the loop, the belt being held, meanwhile, firmly but yieldably, between the two wheels. The next advance of the belt moves this filled loop out of the machine and the filled belt, as it is delivered, is received in a suitable receptacle.

To place the machine in operation, it is assumed, for the purposes of description, that the end loop of the belt contains a fully inserted cartridge and that the next loop contains a partially inserted cartridge. The first loop is placed between the two feed wheels, the spring arm being fastened down by its latch and the belt being inserted in its guide with its inner edge between the jaw members 26, the clip 11 holding the belt flat. Cartridges are fed into the chute and the driving crank 19 is turned by its handle 18. The plunger 40 makes its back stroke and the shoulder 41 engages the heel of the carrier to swing the next cartridge over to the dotted line position of Fig. 1. At about this time the cam 16 has come into a position to swing the ratchet lever down to advance the feed wheels one step which delivers the first loop and advances the next and partially filled loop to a position between the wheels. The plunger 40 then makes its forward stroke and meanwhile the cam 37 acts on the bell-crank lever 35 to move forward the plate 25 and the needle bars 26, thus driving the needles into the belt. As the plunger advances, it simultaneously drives the second cartridge fully into the belt by the engagement of its end with the butts of the cartridge, and advances the third cartridge, by the engagement of the shoulder 41 with the cartridge rim, to separate the needle bars 26, thus opening the loop, and to partially enter the loop. Toward the end of this forward stroke of the plunger, it performs a third action, namely, the return of the carrier by the engagement of the shoulder 42 with the heel of the carrier. Meanwhile, and near the finish of this stroke, the cam 37 has released the bell-crank lever and the plate 25 with the needle bars has returned to former position, thus withdrawing the needles from the belt. This completes a cycle of the ma-

chine and it is now in the same condition as at the start except that the three cartridges involved have advanced a step and a fourth cartridge is in the full line position of Fig. 1 ready for a repetition of the operation described. The operation is continuous, as long as the crank is turned, until the belt is completely filled.

What is claimed is:

1. In a cartridge belt filling device, the combination with a plurality of separable members between which the belt passes, of means associated therewith for seizing each side of a belt loop in a plurality of points, thereby to open the loop effectively upon separation of said members.

2. In a cartridge belt filling device, the combination with a plurality of separable members between which the belt passes, of means associated therewith for seizing each side of a belt loop in a plurality of points, not all of said points being in a line parallel with the path of the belt's travel, thereby to open the loop effectively upon separation of said members.

3. In a cartridge belt filling device, the combination with a plurality of separable members between which the belt passes, of a plurality of needles carried by each of said members for seizing each side of a belt loop in a plurality of points, thereby to open the loop effectively upon separation of said members.

4. In a cartridge belt filling device, the combination with a plurality of separable members between which the belt passes, of a pair of complementary needles carried by said members for seizing the loops of the belt, and a second pair of complementary needles carried by said members in a different plane from the plane of the first pair, also for seizing the belt loops, said needles coöperating to open the loop effectively upon separation of said members.

5. In a cartridge belt filling device, the combination with a plurality of separable members between which the belt passes, of a pair of complementary needles carried by said members at an angle to the belt for seizing the loops thereof, and a second pair of complementary needles carried by said members at a different angle to the belt, also for seizing the loops thereof, said needles coöperating to open the loop effectively upon separation of said members.

6. In a cartridge belt filling device, a plurality of separable members between which the belt passes, a plurality of needles carried by each of said members, means for driving said needles into the sides of a belt loop, and means for separating said members, thereby to open the loop.

7. In a cartridge belt filling device, a plurality of separable members between which the belt passes, a plurality of needles car-

70

130

ried by each of said members, means for driving said needles into the sides of a belt loop and for withdrawing the same, and means for separating said members while 5 said needles are engaging the belt, thereby to open the loop.

8. In a cartridge belt filling device, a plurality of separable members between which the belt passes, a plurality of needles carried by each of said members, means for moving said members to drive said needles into the sides of a belt loop, and means for advancing a cartridge for insertion into the loop, said members being separated by the 15 advance of said cartridge, thereby to open the loop.

9. In a cartridge belt filling device, a plurality of loop seizing members for each side of the belt, means for causing said members 20 to seize the belt loops at a plurality of points not all in a line parallel with the path of the belt's travel and means for separating said loop seizing members to open the loop.

10. In a cartridge belt filling device, a plurality of separable members between 25 which the belt passes, a plurality of needles carried by each of said members, not all of said needles having the points in a line parallel with the path of the belt's travel, 30 means for driving said needles into the sides of a belt loop, and means for separating said members, thereby to open the loop.

11. In a cartridge belt filling device, a plurality of separable members between 35 which the belt passes, a pair of complementary needles carried by said members, a second pair of complementary needles carried by said members in a different plane from the plane of the first pair, means for driving 40 said needles into the sides of a belt loop, and means for separating said members, thereby to open the loop.

12. In a cartridge belt filling device, a plurality of separable members between 45 which the belt passes, a pair of complementary needles carried by said members at an angle to the belt, a second pair of complementary needles carried by said members at a different angle to the belt, means for driving 50 said needles into the sides of a belt loop, and means for separating said members, thereby to open the loop.

13. In a cartridge belt filling machine, a plurality of separable members between 55 which the belt passes, a plurality of needles carried by each of said members, not all of said needles having their points in a line

parallel with the path of the belt's travel, means for moving said members to drive said needles into the sides of a belt loop, 60 and means for advancing a cartridge for insertion into a loop, said members being separated by the advance of the cartridge, thereby to open the loop.

14. In a cartridge belt filling machine, a plurality of separable members between which the belt passes, a pair of complementary needles carried by said members at an angle to the belt, a second pair of complementary needles carried by said members at 70 a different angle to the belt, means for moving said members to drive said needles into the sides of a belt loop, and means for advancing a cartridge for insertion into a loop, 75 said members being separated by the advance of the cartridge, thereby to open the loop.

15. In a cartridge belt-filling device, means for opening the loops of the belt, including means for seizing each side of a 80 loop in a plurality of points, and means for pushing a cartridge into the opened loop.

16. In a cartridge belt-filling device, means for opening a belt loop, including a plurality of loop-seizing needles for each 85 side of a loop, and means for pushing a cartridge into the opened loop.

17. In a cartridge belt-filling device, means for opening the loops of the belt, including means for seizing each side of a 90 loop in a plurality of points, not all of said points being in a line parallel with the path of the belt's travel, and means for pushing a cartridge into the opened loop.

18. In a cartridge belt-filling device, 95 means for opening the loops of the belt, including a pair of complementary needles for seizing a loop and a second pair of complementary needles in a different plane from the first pair also for seizing the loop, and 1 means for pushing a cartridge into the opened loop.

19. In a cartridge belt-filling device, means for opening the loops of the belt, including a pair of complementary needles located at an angle to the plane of the belt for seizing a loop, and a second pair of complementary needles at a different angle to the belt also for seizing the loop, and means for pushing a cartridge into the opened loop. 1

In testimony whereof, I have hereunto set my hand.

GEORGE C. BLICKENSDERFER.
